US00D774520S

(12) **United States Design Patent** (10) Patent No.: **US D774,520 S**
(45) Date of Patent: **** Dec. 20, 2016**

(54) **DISPLAY SCREEN OR PORTION THEREOF
WITH GRAPHICAL USER INTERFACE**

(71) Applicant: **Samsung Electronics Co., Ltd.**,
Suwon-si (KR)

(72) Inventors: **Sung-Min Kim**, Seoul (KR); **Han-Gyul
Kim**, Seoul (KR); **Min-Hee Lee**, Seoul
(KR); **Yun-Jae Lee**, Seoul (KR)

(73) Assignee: **Samsung Electronics Co., Ltd.**,
Suwon-si (KR)

(**) Term: **15 Years**

(21) Appl. No.: **29/529,570**

(22) Filed: **Jun. 9, 2015**

(30) **Foreign Application Priority Data**

Feb. 27, 2015 (KR) 30-2015-0010294

(51) LOC (10) Cl. **14-04**

(52) U.S. Cl.

USPC **D14/485**; D14/492

(58) **Field of Classification Search**

USPC D14/485-495

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The broken line showing of the display screen is for environmental purposes only and forms no part of the claimed design.
